UNITED STATES PATENT OFFICE

JAMES LESLIE EMBLY, OF WAYNESBORO, PENNSYLVANIA, ASSIGNOR OF ONE-HALF
TO H. H. SHOCKEY, OF WAYNESBORO, PENNSYLVANIA

SIPHON VALVE

Application filed March 26, 1929. Serial No. 350,002.

In the operation of siphon valves, such as is shown in Patent No. 1,258,232, difficulty has been experienced in the breaking of the siphon as soon as the opening in the top of 5 the working cylinder through which the valve stem protrudes is above the water level. If this opening is provided with ordinary packing stuffing means the valve acts sluggish, or fails to act at all on account of its light weight, 10 and, by much experimentation, I have discovered that the difficulty may be overcome as herein set forth; and, further, that the device that I have hereinafter described is extremely 15 useful in many other applications where a sealing device is required which is alternately above and below water level.

The object of my invention is the providing of a fluid seal to an operative member subjected to fluid and gaseous surroundings, as 20 the case may be.

A further object of my invention is the providing of an improved siphon valve for flush tanks.

A further object of my invention is the providing an improved siphon valve for flush tanks which will empty the tank without breaking the siphon before the inlet portion thereof reaches the surface of the water.

A further object of my invention is an improved discharge portion of a siphon valve whereby the same is made to enable easier construction and a more stable operation.

With the foregoing and other objects in view, my invention consists of the novel construction, combination and arrangement of parts as hereinafter specifically described and illustrated in the accompanying drawings, wherein is shown the preferred embodiment 35 of my invention, but it is understood that changes, variations and modifications can be resorted to which come within the scope of the claim hereto appended.

In the drawings of the herein-described 45 embodiment of my invention, Figure 1 is a sectional view in side elevation of my improved siphon valve attached to a flush tank; Fig. 2 is a horizontal sectional view taken through 2-2, of Fig. 1; and Fig. 3 is a horizontal sectional view taken through 3-3, of

Fig. 1, and particularly shows the piston or valve support.

Similar numerals refer to similar parts throughout the several views.

1 is the flush tank. 2 is the cylinder. 3 is 55 the inlet in cylinder 2. 4 is the piston or valve support. 5 is the loose valve or piston which operates on valve stem 6 loosely and is supported on valve support 4. Valve support 4 consists of an open supporting member, 60 such as a spider, as shown in Fig. 3, and is secured to valve stem 6 and operates as a skeleton piston in cylinder 2 supporting the actual piston or loose valve 5. 7 is the cylinder head, in the view shown integral with the cylinder. In cylinder head 7 is an opening 8 through which operates valve stem 6. Around opening 8 is a cup or reservoir member 9 of sufficient size to hold a liquid in a quantity sufficient to supply leakage around valve stem 6 operating in opening 8 while the fluid in the tank is being discharged from the top of said reservoir member to the inlet or suction of the cylinder, thereby preventing air entering the cylinder before the tank is 65 emptied. This reservoir member is below the surface of the water when the tank is at its normal filled elevation, that is a point just below the turn of the siphon, thereby said reservoir is always maintained full of fluid excepting when the tank is being emptied, or is empty; it thus provides a fluid seal so long as there is fluid in the reservoir member 9.

At the end of valve stem 6, which is attached to the piston, is means 17 for attaching the pull-cord or chain for flushing means.

10 is the discharge leg of the siphon which passes through flush tank 1 and is provided with means for making water-tight at that point, as shown, consisting of flange 11, threaded portion 12 and lock-nut 13, suitable packing being used on setting up the lock-nut.

It is preferable that discharge leg 10 be 95 substantially straight and of a less diameter or carrying capacity than the other members leading thereunto. 14 is the top bend of the siphon. 15 is the portion connecting the top bend 14 to cylinder 2.

The operation of my invention is as follows:

The siphon valve being properly installed in the flush tank and means being provided for admitting the fluid therein to a specific, predetermined level, which may be accomplished by a ball float or other well-known means concerning which nothing is claimed herein, the fluid is maintained in the flush tank at or about the level shown by the broken line 16—16. The piston 4 and valve 5 are at the lower end or extremity of cylinder 2 near inlet 3, the cylinder 2 connecting member 15 to the point of 16—16 and the reservoir member 9 is full of fluid. Upon pulling the pull cord or chain through means 17 the piston rod with its attached valve support and valve resting upon the same is pulled upward lifting with it the fluid in the upper end of the cylinder which flows through connecting member 15, top bend 14, and down discharge leg 10 of the siphon, causing a siphon action to take place which continues sucking the fluid through valve support 4 and connecting portion 15, the valve 5 being sucked or maintained near the upper portion of the cylinder partially tipped on the valve stem, as the same fits loosely thereon, thus forming no obstruction to the flow of the fluid. Upon the ceasing of the flow of the fluid, which will seek its level at the inlet pipe of the cylinder, and upon releasing the pull cord the valve support immediately descends to its normal position and the valve or piston drops into its normal place.

Again calling attention to the cup or reservoir 9, as the fluid in the flush tank recedes below level 18—18 fluid is held in reservoir 9 and is drawn therefrom only by the leakage around valve stem 6; as the movement of the fluid is very rapid in the cylinder portion and siphon and the leakage around valve stem 6 in opening 8 is very slow, the flush tank will be emptied a considerable time before the fluid in reservoir 9 is emptied therefrom in the performance of its function as a sealing means for opening 8.

In use the pull cord or chain is ordinarily released immediately after pulling. This returns valve support 4 and valve stem 6 to normal position; the weight of these members is carried by auxiliary valve 19 on the valve stem 6 seating on a seat formed in opening 8. This auxiliary valve 19 when seated assists in preventing air or fluid passing through opening 8, thus insuring a stopping or preventing a leak at that point when it is seated.

Having thus described my invention, what I claim and desire to secure by Letters Patent is:

A siphon for flush tanks comprising a cylinder open at its lower end and having an inverted U-shaped conduit attached to its upper end, said conduit extending down be-

low the lower end of the cylinder and providing a siphon for the cylinder, a piston rod extending into the cylinder, a valve loosely slideable upon the said rod, said valve operating as a piston to move fluid upwardly in said cylinder to start the siphon action when the rod is moved upwardly and to remain in elevated position as the rod descends, being held in elevated position by the force of the water flowing out of the cylinder, a cup positioned around the opening in the upper end of the cylinder through which the rod extends and a valve secured on the rod and adapted to seal the opening through which the rod extends to prevent water from flowing into the cylinder, said valve also serving to support the rod in the cylinder when in its lowermost position, substantially as set forth.

JAMES LESLIE EMBLY.
